Primary Examiner — Clare E Heflin(74) *Attorney, Agent, or Firm* — Oyen Wiggs Green & Mutala LLP(57) **CLAIM**

The ornamental design for a suspended luminaire, as shown and described.

DESCRIPTION

FIG. 1 is a top view of the suspended luminaire showing our new design;

FIG. 2 is a left side view thereof, the right side view being a mirror image;

FIG. 3 is a front view thereof, the rear view being a mirror image;

FIG. 4 is a bottom view thereof; and,

FIG. 5 is a bottom, front, right perspective view thereof, the bottom, front, left perspective view being a mirror image. The broken lines shown in FIG. 1 depict portions of the suspended luminaire that form no part of the claimed design. The suspended luminaire is shown with symbolic break lines along its width. The appearance of any portion of the article between the break lines forms no part of the claimed design.
